CLAIM

The ornamental design for an interchangeable lens for camera, as shown and described.

DESCRIPTION

FIG. 1 is a front perspective view of an interchangeable lens for camera, showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a rear perspective view thereof.

The dot-dashed lines show the boundary of the claim and form no part the claimed design. The even dashed broken lines shown in the drawings are included for the purpose of illustrating portions of the interchangeable lens for camera that form no part of the claimed design.

1 Claim, 8 Drawing Sheets
